UNITED STATES PATENT OFFICE.

CHARLES A. LITTLEFIELD, OF LOWELL, MASSACHUSETTS, ASSIGNOR TO THE DRAPER COMPANY, OF PORTLAND, MAINE, AND HOPEDALE, MASSACHUSETTS.

WARP STOP-MOTION FOR LOOMS.

SPECIFICATION forming part of Letters Patent No. 643,300, dated February 13, 1900.

Application filed November 3, 1899. Serial No. 735,656. (No model.)

To all whom it may concern:

Be it known that I, CHARLES A. LITTLEFIELD, of Lowell, county of Middlesex, and State of Massachusetts, have invented an Improvement in Warp Stop-Motions for Looms, of which the following description, in connection with the accompanying drawings, is a specification, like letters on the drawings representing like parts.

10 In another application, Serial No. 735,655, filed by me concurrently herewith, I have shown warp-stop-motion mechanism wherein the detectors are each maintained inoperative by engagement with a pair of crossed warps 15 at their crossing, the crossing being formed by the division of the warps into two groups by the leasing means, the latter being shown as the usual or well-known lease-rods.

20 In my present invention the detectors are maintained inoperative by engagement with crossed warps; but the feeler herein is shown as moved in one direction by warp tension and oppositely by some other means, as a spring, a released detector engaging and arresting 25 the spring-impelled movement of the feeler to thereby effect the operation of suitable stopping means.

I have in my present invention shown the feeler as operating also as one of the leasing 30 devices, it acting similarly to the expansible lease-rod, one form of which is shown in United States Patent No. 401,351, granted April 16, 1889.

The particular manner in which the detectors are normally held inoperative is not herein claimed broadly, as the same is made the subject-matter of claims in my other application hereinbefore referred to.

Figure 1 is a sectional view of a loom, taken 40 from front to rear, showing one embodiment of my invention applied thereto. Fig. 2 is a sectional detail taken on the line $x-x$, Fig. 1, looking toward the right, the warps being omitted; and Fig. 3 is an enlarged perspective detail showing the manner in which the detectors engage a pair of crossed warps.

I have herein shown my invention as applied to a loom as the most general use thereof; but my invention is not restricted to such 50 use or application.

The loom-frame A, the breast-beam A^{40} , the lay A^3 , the lay-swords A^4 , one of which is herein shown, the harnesses H, and the shipper S are and may be of any usual or well-known construction, the shipper operating 55 belt-shifting means (not herein shown) to stop the loom when the shipper is released from its usual holding-notch. The knock-off lever a , pivotally fulcrumed on the loom side at a^x , is shown as jointed at a' to the knock-off rod or 60 shaft a^2 , mounted to move longitudinally in suitable bearings a^3 of the loom-frame, the said knock-off rod having mounted thereon at its rear end a dog a^4 , which is free to rock upon the rod and move longitudinally there- 65 with, said dog being shown in Figs. 1 and 2 as extended inward through a hole a^{20} in the loom side.

I have herein shown a reciprocating bunter b as connected with some part of the lay—as, 70 for instance, the lay-sword A^4 , pivotally connected thereto at b^x , the bunter being supported by and sliding in a guide-support b^2 , secured to the loom side, the rear end of the bunter being adapted to at times engage the 75 dog a^4 to move the knock-off rod longitudinally in the direction of the arrow 10, Fig. 1, to effect the stopping of the loom.

The leasing means for the warps is herein shown as comprising a lease-rod L of usual 80 construction and an expansible lease-rod, herein shown as comprising a flat bar or plate c, extending across the loom between the lease-rod L and the whip-bar W and fixedly supported on upright stands c' , and a feeler 85 f, pivotally connected at f' with the bar c and normally lifted at its free edge or separated from the bar or plate c by one or more springs s, (see Figs. 1 and 2,) the feeler being connected by a link c^x with the dog a^4 . 90 The warps are divided into two groups, the warps w of one group passing over the feeler and under the lease-rod L, while the warps w' in the other group pass over the rod L and under the bar or plate c, so that between the 95 two leasing devices the warps of the two groups cross each other in pairs, as at w^x , Fig. 3. The spring or springs s normally operate to lift the free edge of the feeler and to maintain the dog a^4 out of the path of move- 100

ment of the bunter b , and as the filling is beaten in the tension upon the warps acts upon the feeler to depress the same against the lifting-spring, so that the dog a^4 is moved 5 into the bunter-path. This rocking of the dog into and out of the feeler-path is effected at each pick while the apparatus is running properly.

The apparatus is controlled by a series of 10 detectors d , herein shown as pivoted at their lower ends upon a rod or support d^x , secured to the brackets d' , fast on the loom side, the detectors engaging two crossed warps at their crossing w^x (see Fig. 3) and being maintained 15 thereby in inoperative position, the detector crossing one of the warps, as w , on the side opposite to that crossed by the other warp, as w' , of the part.

Manifestly the detector will be held from 20 operative movement so long as its part of the controlling-warps remains intact, failure of either warp of the part releasing the detector, which swings by gravity toward the rear of the loom, as herein shown.

25 Each detector is notched or hooked at or near its upper end to form a shoulder d^2 in its edge turned toward the feeler, and the front edge of the latter is provided with an upturned lip f^x .

30 Supposing now that a warp breaks, its detector will be released and will swing rearwardly on its pivot toward and against the feeler, and either on that pick or the next succeeding pick the depression of the feeler 35 by warp tension will carry the lip f^x below the shoulder of the released detector, so that upward movement of the feeler will be arrested. The dog a^4 will in consequence be held in its lower position in the path of the

40 bunter b as the lay moves back, and the bunter, striking the dog, will operate to move the knock-off rod a^2 in the direction of the arrow 10, Fig. 1, to swing the lever a on its fulcrum and release the shipper to thereby 45 stop the apparatus. When the detector is engaged by the feeler, as described, it will be subjected to tensile strain, so that there will be no danger of bending or buckling said detector, although, as a matter of fact, in my

50 present invention the only strain brought upon the detector is that sufficient to prevent return of the feeler to the position shown in Fig. 1.

The feeler and the cross-bar to which it is 55 pivotally connected constitute an expanding lease-rod operating substantially in the manner shown and described in the United States patent hereinbefore referred to, and I do not claim an expansive lease device *per se*, the

60 same not being of my invention.

The shipper, the knock-off device therefor, and the bunter constitute, with the usual belt-shifting device, stopping means actuated by or through engagement and arrest of the 65 feeler by the release-detector.

Modifications or rearrangements of the structure herein shown may be made with-

out departing from the spirit and scope of my invention.

Having fully described my invention, what 70 I claim as new, and desire to secure by Letters Patent, is—

1. In a warp-stop-motion mechanism, a feeler moved in one direction by warp tension, a spring to move it oppositely, a series of detectors maintained inoperative by intact warps, a released detector engaging and arresting spring-impelled movement of the feeler, and stopping means actuated by or through such 75 arrest of the feeler.

2. In a warp-stop-motion mechanism, a feeler moved in one direction by warp tension, a spring to move it oppositely, a series of rocking, shouldered detectors maintained inoperative by intact warps, the shoulder of a released detector engaging and arresting the feeler, while the detector is subjected to tensile strain, and stopping means actuated by or through such arrest of the feeler. 85

3. In a warp-stop-motion mechanism, a movable feeler extended beneath and transversely to the warps and intermittently depressed by warp tension, a spring to lift it, a series of angularly-movable detectors maintained inoperative by intact warps, a released detector 95 engaging and arresting spring-impelled movement of the feeler, and stopping means actuated by or through such arrest of the feeler. 90

4. In a warp-stop-motion mechanism, a movable feeler extended beneath and transversely 100 to the warps, and intermittently depressed by warp tension, a spring to lift it, a series of angularly-movable detectors maintained inoperative by intact warps, a released detector 105 engaging and arresting spring-impelled movement of the feeler, and stopping means, including a knock-off rod provided with a dog controlled by the feeler, and a bunter, arrest of the feeler positioning the dog in the path of the bunter, to operate the knock-off rod. 110

5. In a warp-stop-motion mechanism, a lease-rod, a movable feeler parallel thereto to lease the warps and intermittently moved in one direction by warp tension, a spring to move it oppositely, a series of detectors maintained 115 inoperative by the engagement of each with a pair of warps at their crossing between the lease-rod and feeler, a detector released by failure of one of the pair of its controlling-warps engaging and arresting movement of 120 the feeler, and stopping means actuated by or through such arrest of the feeler.

6. In a warp-stop-motion mechanism, a lease-rod and a leasing-feeler moved in one direction by warp tension, a spring to move it oppositely, a series of pivotally-mounted detectors each maintained inoperative by engagement with a pair of warps at their crossing between the leasing members, a released detector engaging and arresting the spring-impelled movement of the feeler, the detector being subjected to tensile strain, and stopping means actuated by or through such arrest of the feeler. 125 130

7. In a warp-stop-motion mechanism, leasing members to separate the warps into groups, one of said members including a feeler spring-actuated in one direction and moved oppositely by warp strain in beating up, a series of detectors maintained inoperative by engagement with a warp of each group at their crossing between the leasing members, a released detector engaging and arresting the normal movement of the feeler, and stopping means, actuated by or through such arrest of the feeler.

8. In a warp-stop-motion mechanism, leasing devices to separate the warps into groups, one of said devices including a spring-controlled member, a series of detectors maintained inoperative by engagement with a warp of each group at their crossing between the leasing devices, a detector when released engaging and arresting normal movement of the spring-controlled member, and stopping means, actuated by or through such arrest of the said member.

9. In a warp-stop-motion mechanism, leasing members to separate the warps into groups, one of said members having a part mounted to rock, a series of detectors main-

tained inoperative by engagement with a warp of each group at their crossing between the leasing members, a detector in abnormal position engaging and arresting the normal movement of the rocking part, and stopping means actuated by or through such arrest of the rocking part.

10. In a warp-stop-motion mechanism, a lease-rod, a rocking feeler parallel thereto to lease the warps and intermittently moved in one direction by warp tension, a spring to move it oppositely, an upturned lip on the free edge of the feeler, a series of pivotally-mounted hooked detectors each upturned to engage a warp in each group at their crossing between the rod and feeler, failure of a warp of a pair releasing its detector, the hook of the latter engaging the lip of and arresting the feeler, and stopping means actuated by or through such arrest of the feeler.

In testimony whereof I have signed my name to this specification in the presence of two subscribing witnesses.
